UNITED STATES PATENT OFFICE.

WILLIAM BARDSLEY, OF KEARNEY, NEW JERSEY, AND WARREN K. CROFFORD, OF NEW YORK, N. Y.

HATCHWAY-DOOR MECHANISM.

SPECIFICATION forming part of Letters Patent No. 469,224, dated February 23, 1892.

Application filed June 1, 1891. Serial No. 394,717. (No model.)

To all whom it may concern:

Be it known that we, WILLIAM BARDSLEY, a resident of Kearney township, New Jersey, and WARREN K. CROFFORD, a resident of New York, in the county of New York and State of New York, citizens of the United States, have invented certain new and useful Improvements in Hatchway-Door Mechanism, of which the following is a specification.

- 10 The invention relates to improvements in hatchway-door mechanism; and it consists in the devices hereinafter described and particularly pointed out in the claims, by which the doors at the various floors of the building may be automatically opened and closed during the ascent and descent of the elevator hoist or carriage, and when closed will effectually cover the space outlined by the hatchway-frames.
- 15 The leverage mechanism hereinafter described for opening and closing the doors is especially adapted for swift-running elevators and in use has proven to be particularly efficacious.
- 20 To produce effective door opening and closing mechanism for swift-running elevators has proven to be an important and difficult problem, and the accomplishment of this object is the purpose of the present invention.
- 25 Referring to the accompanying drawings, Figure 1 is a central vertical section of an elevator-shaft employing the mechanism constituting the invention, the hoist or carriage being illustrated in its initial position on its
- 30 ascent and descent by full and dotted lines, respectively. Fig. 2 is a like view of same, the lever mechanism being shown in the closed position it is caused to assume by the ascending or descending hoist or carriage, which is in this
- 35 figure also illustrated by full and dotted lines, respectively. Fig. 3 is a transverse section of same on the dotted line 3 3 of Fig. 1, looking downward and showing particularly the devices on the door for closing the space outlined by the hatchway-frame so as to prevent all draft through the shaft when the door is closed. Fig. 4 is a like section of same on the dotted line 4 4 of Fig. 2, looking downward. Fig. 5 is a detached side elevation of the
- 50 main operating-lever for opening and closing the door; and Fig. 6 is a detached edge view of same.
- 55 In the drawings, A designates the elevator-shaft; B, the hoist or carriage; C C, the vertical guides for same; D, the hoist-rope; E, the hatchway-door, and F the hatchway-door frame. The door E is secured by hinges G to the frame F, and carries at its under surface and adjacent to its center the roller H, which is set at the inner end of the slot I cut in said door and boxed over by the cover J, as shown more particularly in Figs. 1 and 3. The roller H is engaged by the arch K, secured to the upper end of the carriage or hoist B during the ascent of the latter. It will be observed on reference to Fig. 1 that the roller H is as nearly as possible above the center of the arch K, and that upon the ascent of the hoist the arch will, while opening the door E, permit the roller to move down it and prevent the noise and jar which would result were the arch to scrape against the surface of the door. The slot I during the ascent of the hoist B receives the edge of the arch K after the door has been partly opened and is continuing its movement, and hence it is that the roller H may be placed near to the center of the door and an arch of considerable size be employed. In the ascent of the hoist B the arch K opens the door and closes the lever mechanism to the position shown in Fig. 2, leaving an unobstructed passage for the hoist.
- 60 The mechanism for opening the door during the descent of the hoist or carriage B consists of the pivoted rocking lever L, the rod M, connecting the lower and shorter arm of said lever with the upper surface of the door, and the frame N, secured to the lower surface of the hoist and carrying at its lower inner end the roller O to engage the upper portion of said lever L, as shown in Fig. 1. The lever L is provided intermediate its sustaining-pivot P and its upper end with the roller Q, and, as will be observed in Fig. 1, the said lever has a convex curve between the roller Q and its upper end and an opposite curve between said roller and the pivot P. We have therefore, for convenience, termed said lever L

- 95

as being "S-shaped." The lever L between its roller Q and upper end has a rod R, upon which is arranged the counterbalance-weight S, which is capable of adjustment on said rod, 5 according to the weight of the door, by means of the set-screw T. The lower arm or extension of the lever L is provided with the adjustable slide V, connected with the lower end of the spring W, whose upper end is secured 10 to the threaded eyebolt X, passing through the plate a and carrying the lock-nut b. The bolt X is therefore adjustable, and hence it will be observed that the tension of the spring W may be adjusted at either or both ends, if 15 desired, so that the door may be balanced at its different angles of motion, the spring contracting and expanding with the opening and closing of the door and affording a variable assistance and resistance under the 20 changing line of motion of the same. Upon the descent of the hoist or carriage B the roller O first rides along and depresses the upper curved end of the lever L, as shown in Fig. 1, after which the edge of the frame N 25 moves on the roller Q in the further depression of said lever, as shown in Fig. 2. The depression of the upper end of the lever L operates to draw the connecting-rod M upward and open the door E, as shown, in order that 30 the hoist may have a free passage downward. After the hoist has passed downward through the doorway the door will gradually close upon the arch K, and as the said arch recedes the door will finally fully close without material noise or jar and the lever L will assume 35 its initial position.

The door E is provided with the auxiliary hinged doors d e, which open on their own hinges during the opening of the door E and 40 close with the closing of the same to prevent an excess of draft through the elevator-shaft. The door d is provided at its inner end with the raised arm f, engaging one end of the connecting-rod g, whose other end is pivoted to 45 the lug h, secured to the door e. Upon the door E is pivoted the bell-crank lever i, one arm of which is connected by a rod m with the auxiliary door e, while the other arm thereof is pivoted to the rod n, whose outer 50 end curves downward into a recess in the framing F, and is there pivotally secured on a plane lower than that of the surface of the door or the hinges G, as shown in Figs. 1 and 2. During the opening of the door E the rod 55 n draws on the bell-crank lever i and turning the same moves the rod m inward and opens the auxiliary door e, which turning upward on its hinges forces the rod g inward and opens the auxiliary door d. The doors d e 60 thus open simultaneously, and they close in like manner, since upon the closing of the door E the movement of the bell-crank lever i and rods m g is reversed and both auxiliary doors have the closing motion imparted to 65 them at one time.

What we claim as our invention, and desire to secure by Letters Patent, is—

1. In hatchway-door mechanism, the lever L, mounted on a pivot P and having its shorter arm extending beyond said pivot, the longer 70 arm of said lever normally extending upward at an angle and having the convex curve along its outer end and concave curve along its inner end, as shown, combined with the horizontal door in the path of the elevator-carriage, and the rod M, extending downward from said shorter arm to said door, the whole being arranged substantially as and for the purposes set forth. 75

2. In hatchway-door mechanism, the lever 80 L, mounted on a pivot P and having its shorter arm extending beyond said pivot, the longer arm of said lever having at about its center the roller Q and being convex at the outer side of said roller and concave at the inner 85 side thereof, as shown, combined with the horizontal door in the path of the elevator-carriage, and the rod M, connecting said shorter arm and said door, substantially as and for the purposes set forth. 90

3. In hatchway-door mechanism, the S-shaped lever L, mounted on the pivot P and having its shorter arm extending beyond said pivot, combined with the horizontal door in the path of the elevator-carriage, the rod M, 95 connecting said shorter arm with said door, the coiled spring W, exerting an upward pull on said shorter arm, and the slide V, connected with the lower end of the spring W and adjustable on said shorter arm toward or 100 from the pivot P, substantially as and for the purposes set forth.

4. In hatchway-door mechanism, the pivotally-mounted lever L, having its shorter arm extending beyond the sustaining-pivot and its 105 longer arm having both a convex and concave curve, as shown, combined with the rod R beneath the upper curved end of the lever L, the weight S, adjustable on said rod R, and the rod M, connecting said shorter arm with 110 the horizontal door, substantially as and for the purposes set forth.

5. The hatchway-door and the auxiliary doors d e, hinged thereto, combined with the bell-crank lever i, the rod m, connecting one 115 arm of said lever with the door e, the rod n, pivoted to the other arm of said lever and at its outer end secured to the framing on a plane below the surface of the hatchway-door, the arm f on the door d, and the connecting-rod g, engaging said arm f, substantially 120 as and for the purposes set forth.

6. In hatchway-door mechanism, the pivoted lever L, having the shorter arm at one side of its pivot P and the convex and concave curves at the other side of said pivot, combined with the door, the rod M, connecting said shorter arm with said door, the hoist, and the frame N, secured to the lower surface of said hoist and carrying at its lower 130

inner end the roller *O*, substantially as and for the purposes set forth.

7. The hatchway-door and the auxiliary door *e*, hinged thereto, combined with the bell-crank lever *i*, the rod *m*, and the rod *n*, the latter at its outer end being secured to the framing on a plane below the surface of said door, substantially as set forth.

Signed at New York, in the county of New York and State of New York, this 29th day 10 of May, A. D. 1891.

WILLIAM BARDSLEY.
WARREN K. CROFFORD.
